PUTTER

John Paul Mazzotti, Elmsford, N. Y.

Application July 23, 1947, Serial No. 762,921

4 Claims. (Cl. 273—77)

1

This invention relates to improvements in putters, and its object is to provide a better device than has been available heretofore for enabling a golfer to make accurate putting strokes.

The most outstanding obstacle in the completion of a good score has been the failure to master the art of putting. Many a good field game has been lost ultimately on the greens by all sportsmen from a novice to a professional. Attempts have been made to provide devices for practicing putting to overcome this difficulty, and golf clubs provided with "sighting devices" have been suggested. None of these has been successful for various reasons. I have invented what I call a "True line putter." This, as will be disclosed hereinafter, is a golf club provided with a reflector which can be adjusted to suit the stance of the player and which may be folded into the head of the golf club when not in use.

I will describe my invention in the following specification and point out its novel features in claims.

Referring to the drawings,

Fig. 1 is a front elevation of a golf club having a sighting device which is made according to and embodies my invention. In this figure the sighting device is shown as folded into the head;

Fig. 2 is a view similar to Fig. 1, with the sighting device raised into operative position;

Fig. 3 is a sectional plan view of the parts shown in Figs. 1 and 2. The section in this figure is taken on the line 3—3 of Fig. 2;

Fig. 4 is a sectional side elevation of the parts shown in the preceding figures, the section being taken on the line 4—4 of Fig. 3;

Fig. 5 is a view similar to Fig. 4, with the sighting device in another of its operative positions;

Fig. 6 is a side elevation of the parts shown in the preceding figures, with the sighting device closed; and

Fig. 7 is a sectional rear elevation of the non-positive locking device which is shown in some of the preceding figures. The section in this figure is taken on the line 7—7 of Fig. 4.

10 designates the head of a golf club and 11 its shank. The head has a flat base 12, and a striking surface 13 at right angles thereto. The upper surface of the head is designated by the reference numeral 14. In the specific form of the putter shown in the drawings, the head 10 is made of metal, preferably aluminum, and has intermediate its ends a raised portion 15.

This raised portion 15 and the part of the head immediately below it are cut away to form a

2

pocket 16, with flat parallel inner walls 17, and an arcuate surface 18. Indentations 19 are formed in the walls 17 on arcuate lines for a purpose which will be described hereinafter. The rear and top of the pocket are open.

20 designates the sighting device. This has two flat plates 21, 22 joined at one of the edges of each of them, at right angles to each other and joined at opposite edges by a third plate 23 at 45° to the other plates. Perforate bosses 24 are affixed to the plates 21, 22 near the junction thereof for the reception of a pivot pin 25, which extends through the sides of the portion 15 of the head 10 and is parallel to the striking surface 13. Similar perforate bosses 26 are affixed to the plates 22, 23 near the junction thereof. The bosses 26 support a locking device, which will be explained later. 27 is a mirror or reflector on the side of the plate 23 which is remote from the plates 21, 22.

When the sighting device is closed, as shown in Figs. 1 and 6, the plate 21 closes the top of the pocket 16, and the plate 22 closes the back of the pocket. When in this condition the golf club may be used as a putter in the usual manner.

In order to use the sighting device, it may be raised to position the reflector 27 at 45° to the base 12 of the head, as shown in Figs. 2 and 4. When the head is placed upon a level green, the reflector will then be at 45° to the ground level. The club is then brought into proximity to a ball shown in dot-dash lines at B in Figs. 3, 4 and 5. In the form shown, the shaft 11 is in a plane parallel with the striking surface 13, which, when positioned as thus described, will be vertical. The player may then turn the shaft 11 in one direction or the other, as indicated by the double-headed arcuate arrow A in Fig. 3 to bring the reflection of the cup into which it is desired to drive the ball in the center of the reflector 27. The striking face 13 will then be normal to a line between the ball and the cup into which the ball is to be driven.

The player, by maintaining this relative position of the striking face in making the stroke, is assured that the ball will travel in the desired direction. The strength of the stroke may be accurately gauged after a few trials.

In order to maintain the mirror at the desired angle to the striking face, a non-positive locking device is provided. This comprises a pair of plungers 30 slidably mounted in the bosses 26 and pressed outwardly by a spring 31 (see Fig. 7). The ends of these plungers are convex and engage the indentations 19 to hold the mirror at

the desired angle. Other indentations, 19a, may be provided to hold the sighting device in its closed position.

In the foregoing description it has been assumed that the stance of the player is such that when making the desired adjustment, the shaft 11 is in a vertical position. Some players, however, desire to take a position either nearer to the cup or farther from it, and in order to make the device adaptable for such positions, the position of the reflector may be changed from 45° to the striking face to another angle, as shown in Fig. 5. The reflector, however, cannot be moved out of planes which intersect that of the striking surface on lines which are parallel to the base 12 of the head.

The value of this device to the experienced golfer and to the professional is apparent. Likewise, its value to the professional in teaching the amateur cannot be overemphasized.

Various modifications in construction, mode of operation, method and use of an invention may and do occur to others, especially after benefiting from knowledge of such disclosures as that herein presented of the principles involved, but the invention itself is not confined to the present showing.

I claim:

1. A putter having an elongated head with a base and an intersecting striking surface, said head being constructed with a pocket above the base and intermediate its ends and having an open top, a sighting device comprising a plate shaped to fit the open top of the pocket adjustably movable into different positions, supported near one of its edges by a pivot in the head diagonally opposite and parallel with said intersection of the base and the striking surface, and a reflector extending at an angle from the edge of the plate opposite its pivotally supported edge, said plate in one of its positions closing the open top of the pocket.

2. A putter having an elongated head with a base and a flat striking surface intersecting the base at right angles thereto, said head being constructed with a pocket above the base and intermediate its ends and having an open top, a sighting device comprising a plate shaped to fit the open top of the pocket adjustably movable into different positions, supported near one of its edges by a pivot in the head diagonally opposite and parallel with said intersection of the base and the striking surface, and a reflector ex-

tending at an angle from the edge of the plate opposite its pivotally supported edge, said plate in one of its positions closing the open top of the pocket.

5 3. A putter having an elongated head with a base and an intersecting striking surface, said head being constructed with a pocket above the base and intermediate its ends having an open top, and being open at the side of the head opposite its striking surface, a sighting device comprising a pair of plates joined together at substantially right angles to each other shaped to fit the openings in the pocket, adjustably movable into different positions, supported near their junction by a pivot in the head diagonally opposite to and parallel with said intersection of the base and the striking surface, and a reflector extending at an angle from the edges of the plates opposite their joined edges, said plates in one of 10 their positions closing the openings in the pocket.

4. A putter having an elongated head with a base and a flat striking surface intersecting the base at right angles thereto, said head being constructed with a pocket above the base and intermediate its ends having an open top, and being open at the side of the head opposite its striking surface, a sighting device comprising a pair of plates joined together at substantially right angles to each other shaped to fit the openings in the 15 pocket, adjustably movable into different positions, supported near their junction by a pivot in the head diagonally opposite to and parallel with said intersection of the base and the striking surface, a reflector extending at an angle from the edges of the plates opposite their joined edges, said plates in one of 20 their positions closing the openings in the pocket.

JOHN PAUL MAZZIOTTI.
